United States Patent [19]

Kijima et al.

[11] Patent Number: Des. 313,074

[45] Date of Patent: ** Dec. 18, 1990

[54] ULTRASONIC ASPIRATOR FOR
MICROSCOPE NEUROSURGERY

[75] Inventors: Masaichi Kijima, Tokyo; Nobumichi
Yajima, Nagano, both of Japan

[73] Assignees: Aloka Co., Ltd., Tokyo; Ueda Japan
Radio Co., Ltd., Nagano, both of
Japan

[**] Term: 14 Years

[21] Appl. No.: 139,692

[22] Filed: Dec. 29, 1987

[30] Foreign Application Priority Data

Jul. 29, 1987 [JP] Japan 62-30965

[52] U.S. Cl. D24/26

[58] Field of Search D24/26, 28, 51;
128/24 A; 606/169; 604/22

[57] CLAIM

The ornamental design for an ultrasonic aspirator for
microscopic neurosurgery, as shown and described.

DESCRIPTION

FIG. 1 is a perspective view of an ultrasonic aspirator
for microscopic neurosurgery showing our new design;
FIG. 2 is a front elevational view thereof;
FIG. 3 is a rear elevational view thereof;
FIG. 4 is a top plan view thereof;
FIG. 5 is a bottom plan view thereof;
FIG. 6 is a left side elevational view thereof; and
FIG. 7 is a right side elevational view thereof.

FIG. 1

FIG. 2

FIG. 3

FIG. 4

FIG. 5

FIG. 6

FIG. 7
